UNITED STATES PATENT OFFICE.

GEORGE K. NICHOLAS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed November 20, 1920. Serial No. 425,509.

To all whom it may concern:

Be it known that I, GEORGE K. NICHOLAS, a citizen of the United States, residing at Worcester, in the county of Worcester and 5 State of Massachusetts, have invented a new and useful Weft-Detecting Mechanism, of which the following is a specification.

This invention relates to mechanism for detecting substantial exhaustion of the weft 10 carrier in a loom shuttle, and more particularly to certain improvements in weft detecting mechanism of the type shown in the prior patent to Ryon, No. 1,352,536 issued September 14, 1920. The detector therein 15 shown requires careful and accurate adjustment in order to secure good results from the use thereof, and it has sometimes been found difficult to secure close attention and accurate adjustment under actual working 20 conditions.

It is the object of my invention to provide a detecting mechanism with which accurate results may be attained without the necessity of accurate adjustment thereof.

25 It is another object of my invention to provide a detecting mechanism which is readily adapted to operate upon two different kinds of weft, one of which may be quite different in character from the other, 30 and to the attainment of this object I provide an auxiliary detecting member which is preferably removable from the mechanism when the operator so desires.

My invention further relates to arrangements and combinations of parts which will be hereinafter described and more particularly pointed out in the appended claims.

A preferred form of my invention is shown in the drawings in which—

- 40 Fig. 1 is a plan view of my improved detecting mechanism;
 Fig. 2 is a side elevation thereof;
 Fig. 3 is a vertical sectional view taken along the line 3—3 in Fig. 1;
 45 Fig. 4 is a plan view, partly in section, of the movable detecting member; and
 Figs. 5, 6, 7 and 8 are plan views show-

ing the operation of the device under different conditions.

My improved detecting mechanism is particularly designed for use in connection with transfer indicating mechanism of the type shown in the prior patent to Ryon #972,772, dated October 11, 1910. In the present drawings, I have shown an actuator 10 movable vertically in a slot 11 formed in a projection 12 on a casting 13 fixed to the loom frame. A shaft 14 is pivoted in fixed bearings 15 and 16 and is provided with arms 17 and 18 extending upwardly from the opposite ends of the shaft. A rod 19 is pivotally secured to the upper end of the arm 17 and slides in a recess in the casting 13, which recess extends transversely across the slot 11.

In operation, the end of the rod normally extends across the slot 11 in the path of the actuator 10, but is withdrawn from this position when the detecting members (to be described) are engaged by a weft carrier 70 having a sufficient supply of weft thereon. If, however, the rod 19 is allowed to remain in normal position during the downward movement of the actuator 10, the actuator is thereby rendered effective to indicate weft 75 exhaustion to the transfer mechanism.

A spring 20 is secured at one end to a collar on the shaft 14 and at the other end to the bearing 16 and acts to maintain the parts in the position shown in Figs. 1 and 2. 80 A stand 21 is pivoted at 22 to the casting 13 and is maintained in adjusted vertical position by a stop screw 23. A cap or cover 24 is secured to the stand 21 and forms therewith a guideway for a rectangular slide 25.

A detecting member 26 is fixed to the rear end of the box-like slide 25 and a movable detecting member 27 is pivoted at 28 therein. The pivot 28 is preferably provided with an eccentric bearing portion which may be secured in any desired angular position in the slide 25, thus providing for adjustment of the detecting member 27.

relative to the member 26 which is fixed to the slide.

A rod 29 is slidably mounted in the slide 25 and at its front or left hand end it is engaged by the arm 18 on the shaft 14. The rear or right hand of the rod 29 engages the front side of an arm 30 projecting from the movable detecting member 27. A relatively heavy coil spring 31 is mounted on a 10 stop rod 32 threaded in the cover or cap 24 said rod having a shoulder thereon positioned to engage a bracket 33 secured to the slide 25. The spring 31 normally forces the slide rearward until the bracket 33 engages the shoulder of the stop rod 32. The extreme rearward position of the slide may be adjusted by turning the rod in its threaded bearing in the cover 24.

A rod 34 is also movably mounted in the 20 slide 25 and is provided at its rear end with a hook 35 engaging the rear face of the projecting arm 30. The front end of the rod 34 is enlarged to receive a stop screw 36 which engages the front end of the stand 21 and thus limits rearward movement of the rod 34. It may be noted that a projection 37 on the side of the rod 34 forms the rear bearing for the rod 29.

The spring 20 acts through the arm 18 30 and the rod 29 to yieldingly maintain the arm 30 of the movable detector against the hook 35 of the rod 34 and thus also maintains the stop screw 36 against the front end of the stand 21. If the slide 25 is moved forward, the spring 20 tends to swing the movable detector 27 to the position shown in Fig. 8.

All of the parts thus far described are substantially the same as those shown in the 40 Ryon Patent, #1,352,536 and in themselves form no part of my present invention, which consists in providing an additional or auxiliary movable detecting member in the form of a plunger 40 (Fig. 4) slidable in bearings in the movable detecting member 27 and held yieldingly in rearward position by a light coil spring 41. One bearing of the plunger 40 is in the toothed end 27^a of the member 27 and the other bearing preferably 50 comprises an enlarged opening 42 in the body or hub of the member 27, formed at a slight angle to the axis of the plunger and within which the plunger is loosely fitted. With this construction, the plunger 40 may 55 be easily removed by pushing it into the opening 42 and thereafter swinging the outer end so that it will clear the toothed end 27^a of the detector 27. The teeth of the member 27 are commonly set somewhat in advance of the end of the member 26, and the end of the plunger 40 commonly extends to the rear thereof.

Having described the construction of my improved detector mechanism, I will now 60 describe its operation. The parts are shown

in their normal position in Fig. 7, with the stop screw 36 engaging the stand 21 and the slide 25 forced rearwardly until the arm 30 of the movable detector is engaged by the hook 35 and the toothed end 27^a of the detector 27 is moved into engagement with the fixed detecting member 26. If now the detector is engaged by a full weft carrier, as indicated in Fig. 5, the parts will be moved directly forward to withdraw the rod 19 75 from the path of the actuator 10. Under these conditions, the end of the member 36 enters the weft and the teeth on the member 27 engage the weft and prevent swinging 80 movement of said member.

When the weft on the weft carrier is substantially reduced so that the fixed detector 26 engages the barrel of the bobbin, the teeth of the member 27 no longer engage the weft and the member 27 would naturally 85 move to the position shown in Fig. 8. The plunger 40, however, comes into action at this time and the point of the plunger engages the few remaining turns of weft on the weft carrier, still preventing swinging 90 movement of the member 27.

When, however, no weft remains on the detecting portion of the weft carrier, the member 27 swings to the position shown in Fig. 8, leaving the rod 19 in normal position, and the actuator 10 then becomes effective to indicate weft exhaustion. It is here assumed that a small bunch or reserve supply of weft 95 has been wound at the base of the weft carrier as indicated at W in Fig. 6.

It is sometimes necessary to use the same loom with fine weft or filling at one time and with relatively coarse or heavy filling at another time and it is not usually possible to 105 run the coarse filling until the barrel of the weft carrier is entirely uncovered. Under these conditions the plunger 20 is removed whenever coarse filling is used and is replaced for use with fine filling, thus readily 110 adapting the detecting mechanism to different kinds of filling without the necessity of careful adjustment.

Having thus described my invention, it will be evident that changes and modifications can be made therein by those skilled in 115 the art within the spirit and scope of my invention as set forth in the claims, and I do not wish to be otherwise limited to the details herein disclosed but what I claim is:

1. A weft detecting mechanism comprising a slide, a detecting member fixed to said slide, a second detecting member pivotally mounted on said slide to move with said first detecting member and also relative thereto, and a third detecting member mounted for longitudinal yielding movement on said second detecting member.

2. A weft detecting mechanism comprising a slide, a detecting member fixed to said slide, a second detecting member mounted 130

to move with said slide and said first member and also relative to said first member, and a third detecting device yieldingly mounted on said second detector and nor-

5 mally projecting to the rear of said fixed detecting member, said yielding member being removable from said second member and

said second member and said fixed member being also effective to detect substantial weft exhaustion after said yielding member is removed. 10

In testimony whereof I have hereunto affixed my signature.

GEORGE K. NICHOLAS.
